REMOTE TUNING SYSTEM FOR RADIO RECEIVERS

Adolph A. Thomas, New York, N. Y., assignor to
Radio Corporation of America, New York, N. Y.,
a corporation of Delaware

Application April 30, 1930, Serial No. 448,465

12 Claims. (Cl. 250—20)

My invention relates to the art of tuning radio receivers from a distance, and its object is to provide a remote tuning system of simple construction and reliable operation. For this purpose I 5 install in the radio cabinet an electromagnetically balanced circuit arrangement for controlling a switch in the circuit of an electric motor that drives the tuning shaft. The balanced circuit arrangement may comprise a differential relay 10 having a coil in the circuit of a rheostat controlled by the tuning shaft, and a second coil controlled by a manually operable rheostat in the remote tuning device. These coils act in opposite directions on a movable magnetic member which controls the motor switch. When the electromagnetic action of the coils is substantially balanced, the switch is open; when either coil predominates, the switch is closed and the motor runs to actuate the tuning shaft.

20 A manually adjustable station indicator in the remote tuning device determines the position of the associated rheostat arm and thereby controls the strength of current passing through the connected coil of the differential relay. When the 25 relay circuits are closed after the operator has selected a desired station, one of the two coils will overbalance the other and the motor switch is closed. The tuning shaft moves the connected rheostat arm until the current through the associated coil counterbalances the effect of the remotely controlled coil, whereupon the motor switch is opened and the tuning shaft stops instantly in correct position for the selected station. The electric motor always runs in the same direction, so that only a single switch is needed for the 30 differential relay to close and open the same circuit. Another advantage of a non-reversible motor lies in the fact that a universal motor operating on either A. C. or D. C. house-lighting circuits may be used.

The remote tuning device of my invention comprises a small box containing only one or two switches, a rheostat, a volume control, and perhaps also a signal lamp, although the latter is not necessary. In a preferred form of my invention, I use a single rheostat resistance to perform a double function; controlling the current through one of the differential relay coils for selecting a station, and controlling the volume of reproduction. This two-fold operation of the rheostat is controlled by a single knob on top of the box. The knob is first rotated to move an indicator to the desired station mark, and then the knob is pushed in to close the circuits of the relay coils. When the selected station is in tune, the knob is re-

leased and may now be turned to regulate the volume. In other words, a single knob performs the triple function of selecting a station, closing the relay circuits in the receiver, and controlling the loudspeaker volume. The only other finger piece needed on the control box is a switch member for turning the electric power on and off. The control box is operatively connected with the radio cabinet by an electric cable containing only a few wires of low voltage. In one embodiment 10 of my invention, not more than six wires are needed in the cable for complete control of the receiver.

The practical advantages and novel features of my remote control system will be understood from 15 a description of the accompanying drawings, in which

Fig. 1 is a simplified diagram of circuit connections illustrating the principle of operation of my invention;

Fig. 2 is a top view of the remote control box;

Fig. 3 shows a transverse section through the box on line 3—3 of Fig. 2;

Figs. 4 and 5 represent sectional plan views on lines 4—4 and 5—5, respectively, of Fig. 3;

Fig. 6 is a section on line 6—6 of Fig. 5;

Fig. 7 is a fragmentary sectional view on line 7—7 of Fig. 4;

Fig. 8 is a top plan view of the tuning mechanism in the radio cabinet;

Fig. 9 illustrates a front elevation of the tuning mechanism, partly sectioned on line 9—9 of Fig. 8;

Fig. 10 is a vertical section through line 10—10 of Fig. 9;

Fig. 11 is a detached perspective of the insulating block that supports the relay switches of the remote control system;

Fig. 12 shows a fragmentary view of the insulating block, partly sectioned on line 12—12 of Fig. 8;

Fig. 13 is a diagram of circuit connections between the tuning shaft and remote control box;

Fig. 14 illustrates a modified system of volume control; and

Fig. 15 shows diagrammatically another form of differential relay and associated switches for controlling the tuning shaft.

I shall first explain the underlying principle of my invention by referring to Fig. 1, which shows 50 a simplified diagram of circuit connections and is not intended to represent a complete system such as would be used in actual practice. An electric motor 10 in the radio cabinet is operatively connected with a shaft 12 which carries (or other- 55

wise controls) suitable tuning elements 13. These are diagrammatically indicated as variable condensers, which are almost universally employed for tuning purposes in modern radio receivers. It is assumed that the motor 10 drives the tuning shaft 12 at the requisite low speed, and automatic reversing mechanism may be interposed to reverse the rotation of the shaft at each end of the dial. A rheostat R has a rotary contact arm 14 movable in unison with tuning shaft 12, either by being directly mounted thereon, or being otherwise connected thereto in any practical way. The resistance element 15 of the rheostat is connected at one end to a solenoid coil 16 which is connected to one side of battery 17. The other side of the battery is connected to the movable contact arm 14. A second coil 18 is connected at one end to the resistance element 19 of a rheostat R' in the remote control box, and the other end 20 of the coil is connected to one side of a battery 20. The other side of this battery is connected to the rotary contact arm 21 of rheostat R'.

The solenoid coils 16 and 18 are arranged in axial alignment and control a movable magnetic core or armature 22 which is mounted on a lever 23 pivoted at 24. The movements of the magnetic core 22 control a switch comprising a fixed contact 25 and a movable contact 26, which is mounted on (or otherwise connected to) the pivoted lever 23. The fixed contact 25 is so shaped that it is engaged by the movable contact 26 when the magnetic core 22 is drawn into either of the coils 16 and 18. A contracting coil spring 27 normally holds the core 22 centrally of the coils, so that contact 26 is separated from the fixed contact 25. These two contacts constitute a normally open switch in the circuit of motor 10, which is connected to a battery 28. The rheostat arm 21 in the remote control box is operated by a knob or other suitable finger piece and an indicator on the box enables the operator to select a desired station. In Fig. 1 the station-selecting scale or dial is diagrammatically indicated at 29, and the rheostat arm 21 may be assumed to correspond in position to the indicator arm on the control box.

Let us suppose that the switches 30 and 31 are closed and that the rheostat arm 21 has been moved to the position shown in Fig. 1 for tuning in a certain station. Unless the tuning shaft 12 of the radio receiver happens to be in tuning position for the selected station, the rheostat arms 14 and 21 will occupy different positions, so that the current through one of the solenoid coils 16 or 18 will be stronger than the current in the other coil. Consequently, the predominating coil will draw in the iron core 22 and move contact 26 against contact 25. The motor circuit is now closed and the tuning shaft 12 is operated in one direction or the other until the rheostat arm 14 so adjusts the current in coil 16 that the electromagnetic effects of the two coils are balanced or neutralized. When that occurs, the core 22 assumes its normal or neutral position and opens the motor switch 25-26, so that the shaft 12 stops in correct tuning position for the station selected by the operator from the remote control box. The solenoid coils 16 and 18 and the resistances 15 and 19 are so designed that for any position of rheostat arm 21 the opposing electromagnetic effects of the solenoid coils are neutralized when the radio shaft 12 is in tuning position for the selected station. It is immaterial which of the two coils predominates when they are first energized, because the movement of the

core 22 in either direction from its neutral position causes the motor switch 25-26 to be closed. The switches 30 and 31 are normally open and closed simultaneously from the remote control box, as will be explained later in detail. The batteries 17, 20 and 28 in Fig. 1 are shown as separate sources of current to simplify the circuit diagram, but in actual practice the electric power for the remote control circuits is derived from a single source, which may be the house- 10 lighting system.

Figs. 2-7 show the construction of one form of remote control box which comprises a cylindrical body 32 closed by a removable cover 33. One way of fastening the cover in place is to provide it with an annular flange or shoulder 34 adapted to receive fastening screws 35 from the side, so that they do not show on top of the box. The box sections 32 and 33 may be made of sheet metal or molded of insulating material like hard rubber, bakelite, fiber and others. The resistance element 19 of rheostat R' is shown as a fine wire wound on a semi-circular strip 36 which is secured at its ends in a pair of blocks 37 attached to the box in any practical way, as by screws 38. The strip 36 is preferably of flexible insulating material, so that it is normally straight to permit winding of the wire by machine. The wire-wound strip is bent into a semi-circle so that the ends can be inserted in slots 38' of blocks 37 and secured by screws or otherwise. Instead of a resistance wire I may use resistance material like graphite, which gives a fine variation of ohmic values.

The bottom of box 32 is provided with a hollow boss 40 having a recess 41 to receive the lower end of a shaft 42. An extension 43 on this shaft projects through cover 33 and carries a knob or other suitable finger piece 44. The radial arm 45 projecting from knob 44 is arranged to move over the station scale or dial 29. The knob 44 and pointer 45 may be molded as a single piece of bakelite, fiber, hard rubber and the like. The scale 29 carries suitable notations to indicate the various broadcasting stations, as is usual in dials 45 on radio receivers. The shaft 42 is mounted for rotary as well as axial movement, and an expanding coil spring 46 in the hollow post 40 normally holds the shaft in raised or outer position. The rheostat arm 21 has an annular base portion 47 adapted to be mounted on one end of a hub 48 fixed on shaft 42, and screws or other fastening members 49 may be used to connect these parts securely together. The hub 48 may be a separate insulating piece attached to shaft 42, or these two parts may be cast or molded as a unit. A second contact arm 50 having an annular base portion 51 is mounted in a similar manner on the lower end of hub 48, and the function of this second arm is to operate with the resistance element 19 for controlling the volume of reproduction, as I shall explain more fully in due course.

The rheostat arms 21 and 50 are so spaced that only one of them can engage the resistance wire 19 at a time. In the normal raised position 65 of shaft 42, the lower arm 50 is in contact with resistance 19, as shown in Fig. 3. When the knob 44 is pushed in to close the circuits of solenoid coils 16 and 18, the station-selecting arm 21 is moved into contact with resistance 19, as shown 70 in Fig. 6. The pointer 45 indicates not only the selected station, but is also used to indicate roughly the degree of loudness of the reproduction. Referring to Fig. 2, the loudspeaker volume is a minimum when the pointer 45 is at the left and 75

gradually increases as the knob 44 is turned clockwise. One of the blocks 37 supports a pair of insulated spring fingers 52 and 53 arranged to bear against the hub portions 47 and 51 of rheostat arms 21 and 50. For convenience of manufacture, each of these arms and its hub portion may be stamped or pressed from sheet brass or other good conducting metal. The pressure of the spring fingers 52 and 53 against the associated rheostat arms is light enough to permit easy rotation of shaft 42. The spring fingers are so constructed and arranged as to remain in contact with the hub portions 47 and 51 in either axial position of shaft 42, as will be clear from Fig. 6.

A bracket 54 in box 32 supports a switch arm 55, which may be a spring blade secured at one end by screws 56 or otherwise. The free end of spring arm 55 is adapted to engage a fixed contact 57 carried by a bracket or projection 58. The switch-supporting parts 54 and 58 may be formed integral with the body of the box if the latter is molded of insulating composition material. The normal set or tension of spring arm 55 is such that its free end is out of engagement with contact 57. The extension 43 of shaft 42 passes through a hole in switch arm 55 and the spring is locked to the shaft by a cross-pin 59 and the shoulder 60. This connection between switch arm 55 and shaft 42 permits rotation of the shaft without affecting the position of the switch arm. However, when the knob 44 is pushed in, the switch arm 55 is pressed into engagement with contact 57. The switch arm 55 need not be resilient, because the shaft 42 is normally maintained in raised or outermost position by the expanding coil spring 46. On the other hand, the spring 46 may be omitted by making the switch arm 55 sufficiently resilient to hold the shaft 42 in raised position. The purpose of switch 55-57 is to close the circuit through solenoid coil 16 when the knob 44 is pushed in. This will be understood when I describe the wiring diagram of Fig. 13. However, as I shall subsequently explain, the switch 55-57 may be omitted and replaced by a relay switch in a radio receiver.

The cover 33 of box 32 has a window 61 which is closed by a transparent or translucent strip 62 of glass, celluloid, netting, mica, oiled skin or the like. A simple way to hold the strip 62 in place is to insert the side edges in slots 63 formed in the inside of cover 33, and a set-screw 64 locks the strip in position. This will be understood by looking at Fig. 7. Below the window 61 is a small electric lamp 65 mounted in a metal socket 66, which is carried by a flange 67 depending from cover 33. A screw 68 is in good electrical contact with socket 66 and serves as a binding post for a conductor 69. The central contact of lamp 65 bears against a spring finger 70 secured by a screw 71 to a projection 34' on the annular cover flange 34. The screw 71 may also be used as a binding post for a conductor 72. The signal lamp 65 may be supported in any other practical way in box 32, but the mounting just described is simple and permits easy insertion and removal of the lamp after the cover 33 is taken off. While the lamp 65 is not absolutely necessary, the light shining through window 61 tells the operator that the electric power in the radio receiver is on. As shown in Fig. 2, the window 61 is so wide that it can not be fully covered by the rotary pointer 45. A suitable switch 73 in box 32 is controlled by a finger piece 74 extending through a slot 75 in cover 33

to turn the electric power in the radio receiver on and off. It will not be necessary to show or describe the mechanism of switch 73, because many types of switches can be obtained in the market for use in the remote control box.

Referring to Figs. 8-12, the tuning shaft 12 is journalled in bearings 16, and the rear end of the shaft is operatively connected to the armature shaft of the electric motor 10. These connections are indicated in Fig. 8 by a worm 77 mounted on the motor shaft and permanently in mesh with a worm gear 78, which drives the tuning shaft at properly reduced speed. It is assumed that the tuning shaft 12 is automatically reversed when the indicator in the receiver cabinet is at either end of the scale, which usually extends over an arc of 180 degrees. The automatic reversal of shaft 12 may be accomplished either by a reversing switch if the motor 10 is reversible, or by transmission connections interposed between gear wheel 78 and shaft 12 for changing the continuous rotation of the gear into alternately opposite movements of the tuning shaft. In Fig. 8 the rectangular outline 79 indicates diagrammatically any practical mechanism for automatically reversing the rotation of tuning shaft 12 at each end of the dial. For an example of an automatic reversing mechanism suitable in this connection, I refer to my copending application Serial Number 338,391, filed February 8, 1929. By letting the motor shaft run in one direction only, it is possible to use a universal motor adapted to operate equally well on direct current and alternating current.

The driving connections between the electric motor 10 and tuning shaft 12 are such that the latter may be turned by a hand knob 80 on the front panel 81 of the radio cabinet. The knob 80 is connected to a stub shaft 82 which carries a pinion 83 arranged to mesh with a gear wheel 84 fixed on shaft 12. The resistance element 15 of rheostat R may be mounted on the inner wall of front panel 81, and the contact arm 14 is mounted directly on the tuning shaft 12. However, in the broader aspect of my invention, the rheostat arm 14 may be supported independently of shaft 12 and operatively connected thereto in any practical way. In the present instance I have shown the resistance element 15 as a fine wire wound on a flexible insulating strip 85 which is attached at its projecting ends to a block 86, and this block is secured to the inner face of panel 81 by bolts or screws 87. The block 86 is provided with an extension 88 to which a spring finger 89 is attached. The free end of finger 89 bears constantly against the hub portion 90 of rheostat arm 14. I might explain here that when I speak of shaft 12 as the tuning shaft, I do not mean that the tuning elements 13 must be mounted thereon, but I mean any shaft operable to adjust the tuning means of the receiver.

An insulating frame indicated as a whole by 91 is secured to the bottom 92 of the radio cabinet by screws 93 or otherwise. The solenoid coils 16 and 18 are mounted in openings or recesses 94 in frame 91, which may conveniently be molded in one piece of bakelite, hard rubber, fiber and the like. The pivot pin 24 of lever 23 is mounted in a pair of cross-pieces 95 on frame 91. The lever 23 may be a flat bar mounted on a sleeve or bushing 96, which extends between the bridge pieces 95 and thereby prevents lateral movement of the lever. The lower end of the contracting coil spring 27 is connected to a rod 97 which passes through holes 98 near the bot-

tom of frame 91. The reciprocable magnetic core 22 has a slot 99 for the passage of lever 23, which is connected to the core by a pin 100. The lever 23 has a short longitudinal slot 101 to provide the necessary loose play between the reciprocable core 22 and the pivotal movements of the lever. The magnetic core 22 moves in and out of coils 16 and 18 so freely that the tensioned spring 21 quickly restores the lever 23 to normal position when the coils 16 and 18 are deenergized or counterbalanced. The contact 26 may be a short leaf spring attached to lever 23 in any suitable way, as by being inserted in a small block 23' which is secured to the upper end of the lever. The stationary contact 25 is a U-shaped member (for example, a piece of bent brass) set in a recess 102 in frame 91 and held in place by a screw 103, which may also be used as a binding post.

20 The insulating frame 91 has a hole or recess 104 in which a coil 105 and magnetic core 106 are mounted. A pair of spaced ears or lugs 107 on frame 91 support a rod or pin 108 which carries a depending hinge 109. This hinge is a magnetic member or else carries an armature 110 in operative relation to the outer end of magnetic core 106. A switch arm 112 attached to hinge member 109 is adapted to engage a contact 113 mounted on frame 91. The contact 113 may simply be the head of a screw or bolt inserted in a hole 114 in the frame. A tensioned torsional spring 115 on hinge pin 108 normally holds the armature 110 away from magnet 106, so that the switch arm 112 hangs in open position. When the coil 105 is energized, the armature 110 is attracted and the switch arm 112 is moved into engagement with the stationary contact 113.

25 The operative connections between the remote control box and the radio receiver are diagrammatically indicated in Fig. 13, which will now be described. Two service mains 116 and 117 lead from a plug 118 adapted to be inserted in an ordinary house-lighting socket. If necessary, a current rectifier 119 may be interposed. A suitable hand-switch 120 is inserted in lead 116 to turn the electric power on and off for all circuits in the radio receiver and remote control box. The switch 120 may be of any suitable construction and is usually operated from the front panel of the radio receiver. Two conductors 121 connected in shunt across switch 120 and the power supply are supposed to be properly connected to the receiver system to supply the necessary power, as will be understood without further explanation. The service mains 116-117 lead to a suitable voltage reducer 122 for cutting the house-lighting voltage down to an amount low enough for operating the electric motor 10, the differential coils 16 and 18, and the relay coil 105. As a rule that voltage need not be more than ten volts and probably less. The low voltage conductors leading from the reducing device 122 are indicated at 123 and 124. A wire 125 connects the movable switch contact 26 with conductor 123. The associated fixed contact 25 is connected to one terminal of the electric motor 10 by a wire 126, and the other motor terminal is connected by a wire 127 to the low voltage lead 124. I may interpose a clutch coil 128 which operates a clutch member when the coil is energized to connect the motor shaft with the tuning shaft 12. When coil 128 is de-energized, the clutch connection between the motor and the tuning shaft is broken, so that the tuning shaft

30 35 40 45 50 55 60 65 70 75

stops instantly when the motor circuit is interrupted.

A wire 129 connects the contact finger 89 of rheostat R to conductor 124 and the associated resistance element 15 is connected by a wire 130 to one side of coil 16. The other side of this coil is connected by a wire 131 to the switch arm 55 in the remote control box. One side of the other differential coil 18 is connected by a wire 132 to conductor 123, and the other side of this coil is connected by a wire 133 to resistance element 19 in the remote control box. A pair of wires 134 and 135 leading from service main 116 are connected to switch members 112-113, so that the latter are shunted across the hand-switch 120 in the radio cabinet. The relay coil 105 is connected at one side by a wire 136 to a movable switch arm 137, and the other side of the coil is connected to wire 72 which leads to one terminal of signal lamp 65, as previously explained. A stationary contact 138 associated with switch arm 137 is connected by a wire 139 to the low voltage conductor 123. A pivoted cam member 140 operated by the finger piece 74 moves the switch arm 137 to open and closed positions. The parts 137, 138 and 140 may be assumed to represent the switch 73 mounted in the remote control box, but any other practical form of switch may be used. The contact finger 52 in the remote control box is connected by a wire 141 to conductor 124, and the other contact finger 53 is connected by a wire 142 to one side of coil 143. The other side of this coil is connected by a wire 144 to wire 133. The coil 143 is the secondary coil of an audio-frequency transformer 145 in the radio receiving system. The rheostat resistance 19 is shunted across the secondary coil 143, so that by varying the resistance it is possible to vary the volume of reproduction.

40 45 50 55 60 65 70 75 80 85 90 95

When the finger piece 74 is moved to "on" position, switch 137-138 is closed and relay coil 105 is energized to close the power switch 112-113, whereby the radio receiver is connected to the source of electric power supply. Since the lamp 65 is connected in series with relay coil 105, the lighting of the lamp tells the operator that the electric power for the radio receiver is on. It may be advisable to shunt a resistance 146 around the lamp, so as not to disorganize the remote control apparatus if the lamp should happen to burn out. The operator turns knob 44 (without depressing the same) until the pointer 45 indicates the station wanted. As long as the arm 21 is out of contact with resistance 19, the circuits of coils 16 and 18 are open and the motor 10 is not running. However, when the operator depresses knob 44 after having moved it to station-selecting position, the engagement of contact arm 21 with resistance element 19 closes the circuit of coil 18 as follows: Conductor 123, wire 132, coil 18, wire 133, resistance 19, contact arm 21, finger 52, wire 141, return conductor 124. At the same time, the depressing of knob 44 (which now operates like a push button) closes the switch 55-57, thereby closing the circuit of coil 16 through the following connections: conductor 123, wires 139 and 147, contact 57, switch arm 55, wire 131, coil 16, resistance element 15, contact arm 14, finger 89, wire 129, return conductor 124. Unless the station indicated by pointer 45 happens to be in tune, one of the two coils 16 and 18 will predominate in its electro-magnetic effect on the movable core 22, so that the latter will be drawn into the predominating coil and the contact 26 will be moved against contact 25.

The circuit of motor 10 is now closed as follows: Conductor 123, wire 126, through windings of motor 10, clutch coil 128 (if the same is used), and through wire 127 to return conductor 124. 5 The energized motor drives the tuning shaft 12 and with it the contact arm 14 until the latter is in such position that the electromagnetic effect of coil 16 is substantially equal to that of the opposing coil 18, whereupon the magnetic core 22 moves to neutral position and opens the motor switch 25-26. The tuning shaft stops instantly in position for the station represented by the indicator 45 on the remote control box. It takes only a few seconds for any station to be 10 tuned in, and the operator is supposed to hold the knob or button 44 pushed in until he gets the selected station. When the button is released, the rheostat arm 21 and switch arm 55 automatically move to open position and the circuits of coils 16 and 18 are broken, so that no current is 15 wasted after the selected station has been tuned in. The release of button 44 moves the second rheostat arm 50 into contact with resistance 19, so that the operator may now regulate the volume of reproduction by simply turning the knob 44 one way or the other. If a person wants to 20 hunt for a suitable program without caring from what station it emanates, he pushes in the knob 44 and turns it either way from one end of the 25 scale to the other until he gets the kind of broadcasting he likes. The knob 44 is then released and the loudspeaker volume is adjusted by turning the pointer 45 toward loud or soft position. Shoulders 36' on strip 36 engage the arm 21 to 30 limit the rotation of knob 44 to half a revolution between the "0" and "100" marks on the dial.

If the wires 142 and 144 are so connected in the receiver system as to carry a relatively high voltage, I may substitute the volume control arrangement shown diagrammatically in Fig. 14, where a separate rheostat R2 is shunted across the secondary coil 143. This rheostat comprises a resistance element 148 connected by a wire 149 to 45 one side of coil 143, and a pivoted contact arm 150 connected by a wire 151 to the other side of the coil. The contact arm 150 is connected to a reciprocable solenoid core or plunger 152, which is operatively associated with a coil 153. This 50 coil is controlled by a rheostat R3 comprising a resistance element 154 and a rotary contact 155. The source of electric energy for coil 153 is diagrammatically indicated by a battery 156, but in actual practice the coil is connected to the low 55 voltage conductors 123-124 of Fig. 13. A contracting coil spring 157 normally holds the plunger 153 in raised position, so that the contact arm 150 is in position 150' for minimum volume of reproduction. 60 When the coil 153 is energized, the movement of plunger 152 depends upon the strength of current passing through the coil as determined by the position of rheostat arm 155. When the latter is in "loud" position as shown in Fig. 14, the 65 current through coil 153 is a maximum and the plunger 152 is drawn farthest into the coil to move the contact arm 150 to the full line position 150, so that practically all the resistance 148 is included in circuit. Consequently, the volume of 70 reproduction is now a maximum. For any intermediate position of contact arm 155 between the extreme loud and soft positions, the solenoid 152-153 will move the contact arm 150 to a corresponding position on resistance element 148,

so that the volume of reproduction will roughly correspond to the position of controlling arm 155. It is understood that the rheostat arm 155 is operated by the knob 44, the same as contact arm 50. While the volume control system of Fig. 5 14 requires an additional rheostat and solenoid in the radio cabinet, it has the practical advantage that the coil 153 is connected in a circuit of low voltage.

The switch 55-57 in the remote control box 10 can be eliminated and the circuit of coil 16 controlled by a relay switch in the radio receiver. This alternative arrangement is diagrammatically illustrated in Fig. 15, where only so much of Fig. 13 is shown as is necessary to understand 15 this modification. Corresponding parts in Figs. 13 and 15 are indicated by like reference numerals. The coils 16 and 18 in Fig. 15 are mounted on a magnetic core or frame 158, and the movable switch contact 26 is in the form of a 20 spring arm carrying an armature 159 adapted to be attracted to the magnetized core 158 when either coil predominates. The conductor 133 of coil 18 contains a relay coil 160 mounted on a 25 magnetic core 161. One side of coil 16 is connected by a wire 162 to a movable switch arm 163, which may simply be a spring blade normally held away from the associated contact 164. The spring blade 163 either is magnetic or carries an armature 165 arranged to be attracted to core 30 161 when coil 160 is energized for closing the circuit of coil 16. In other words, when the knob or push button 44 of the remote control box is pushed in after a station has been selected, the 35 relay 160-161 is energized to close the circuit of the opposing coil 16.

Still referring to Fig. 15, as long as either of the differential coils 16 and 18 predominates electromagnetically, the core 158 is energized to hold the switch arm 26 in closed position, thereby 40 causing the electric motor 10 to drive the tuning shaft 12, as previously explained in connection with Fig. 13. When the shaft is in selected tuning position, the opposing magnetic fields produced in core 158 are substantially balanced or 45 neutralized, and the switch member 26 automatically moves to open position. The use of the relay-operated switch 163-164 for coil 16 dispenses with the wire 131, so that only six wires are needed in the electric cable that connects the 50 remote control box with the radio receiver. The resistance of relay coil 160 in the circuit of coil 18 is counterbalanced in the circuit of coil 16 by an equivalent resistance 166. Otherwise, what has been said for the operation of the system in 55 Fig. 13, applies to Fig. 15. It is understood that Fig. 15 is intended to be substituted in Fig. 13 for switch 55-57 and reciprocable core 22.

It will be clear from the foregoing description that I have provided a simple apparatus for the 60 complete control of a radio receiver at a distance, including not only the selection of a desired station, but also the regulation of loudspeaker volume and turning the electric power for the receiver on and off. Not more than six or seven 65 wires of low voltage are required in the electric cable that connects the remote control box with the radio cabinet. In Fig. 13 the imaginary dotted line 167 is supposed to cut through the cable, so that the lines crossing it are the wires 70 75 that compose the cable. The low voltage of the cable wires makes it absolutely safe to use a cable of any length without special insulation. The use of resistance 19 for selecting a station and regulating the loudspeaker volume simplifies the 75

mechanism inside the control box, which can be made very small and light.

Although I have shown and described certain specific constructions, I want it understood that my invention is not limited to the details set forth. It is to be expected that changes and modifications will probably occur to those engaged in building a remote control apparatus in accordance with my invention, without departing from the scope of the appended claims.

I claim as my invention:

1. A radio receiver having variable tuning elements and a loudspeaker, in combination with a station-selecting device having a rotary finger piece, means for holding said finger piece against lateral tilting, a pair of rotary members simultaneously operated by rotation of said finger piece, said members being separate from said tuning elements, means controlled by one of said members for selecting a station to be tuned in, means controlled by the rotary movements of the other member for regulating the volume of said loudspeaker while the tuned-in station remains in tune, and means for so mounting said finger piece that it remains in any adjusted volume-control position when released.

2. In a tuning device for radio receivers, the combination of a rotary knob mounted so that it can be pushed in, means whereby said knob remains in any rotatably adjusted position when released, spring means for normally holding said knob in outermost position and automatically restoring it to normal position upon manual release thereof, electric mechanism controlled by the rotation of said knob in depressed position for selecting a station to be tuned in, said mechanism including an electric circuit, switch means controlled by the return movement of said knob for opening said circuit, an electric device for regulating the loudspeaker volume, and means operated by the rotation of said knob in normal position for controlling said device independently of said mechanism, which remains in selected tuning position during the operation of said volume-controlling means.

3. A remote tuning box for radio receivers having means for selecting a station to be tuned in, means for controlling the volume of reproduction of a tuned-in station, said two means including a pair of separate contact members and a variable resistance element common to both members, and means whereby said volume-controlling means operates independently of said station-selecting means which remains in selected tuning position during the operation of the volume-controlling means.

4. A remote control device for radio receivers comprising a single adjustable knob capable of rotary movement in either direction, means for holding said knob against lateral tilting, station-selecting means operable by rotation of said knob, volume-control means also operable by rotation of said knob, the degree of volume depending upon the variable angular position of the knob connections whereby said station-selecting means and volume-control means are simultaneously operated by said knob but only one of said means is in operative condition at a time, and means whereby said knob remains in any rotatably adjusted position when released.

5. In radio receiving apparatus having tuning mechanism and a loudspeaker, the combination of a variable electric resistance element, operative connections between said element and said mechanism for tuning in a selected station

by varying the resistance of said element, other operative connections between said element and said loudspeaker for regulating the loudspeaker volume by varying the resistance of said element, and means for controlling either of said connections independently of the other.

6. The combination of a radio receiver having a tuning shaft and a loudspeaker, a rotary spindle mounted to occupy two different axial positions, means for holding said spindle against lateral tilting, a knob on said spindle, means controlled by the rotation of said knob in one axial position for operating said tuning shaft to bring in a desired station, means controlled by the rotation of said knob in its other axial position for regulating the volume of said loudspeaker connections whereby said tuning means and volume-control means are simultaneously operated by said knob but only one of said means is in operative condition at a time, and means whereby said shaft remains in selected tuning position during the operation of said volume-controlling means.

7. A radio receiver having variable tuning elements and a loudspeaker, electric mechanism for operating said elements, and a device for regulating the volume of said loudspeaker, in combination with a remote control box having a manually operable rotary shaft mounted for axial adjustment to two operative positions, means for preventing lateral movement of said shaft, electric connections controlled by the rotation of said shaft in one axial position for operating said mechanism to tune in any selected station, electric connections operated by the rotation of said shaft in its other axial position to control said volume-regulating device independently of said tuning connections, so that the selected station remains in tune during the volume-regulating operation, and means whereby said shaft remains in any rotatably adjusted position when released.

8. A remote tuning box for radio receivers having a variable resistance element, a movable contact arm arranged on one side of said element for selecting a station, a second movable contact arm arranged on the other side of said element for controlling the volume of reproduction, a common adjustable support for said arms, only one of said arms being normally in engagement with said element, and a finger piece for moving said support out of normal position to a second operative position so as to bring the other arm into engagement with said element, said support being also adjustable by said finger piece to move either contact arm along said element to predetermined position.

9. A remote tuning device for radio receivers having a resistance element, two adjustable contact members associated with said element, manually operable means for adjusting said members in relation to said element, one of said members cooperating with said element to control tuning mechanism in the receiver, the other member cooperating with said element to control the volume of reproduction, and means for so mounting said members that only one at a time engages said element.

10. In a remote tuning box adapted to be operatively connected with a radio receiver, a rheostat comprising a resistance element and a pair of contact arms, a rotary shaft on which said arms are mounted in such a way that only one arm at a time can engage the resistance element, one of said arms being adjustable to select a station to be tuned in by the receiver, the other

arm being adjustable to regulate the volume of reproduction, and a spring support for said shaft to permit axial movement thereof, said support normally holding the volume-control arm in contact with the resistance element.

11. Electric driving mechanism which includes an electromagnetic controlling device comprising a pair of coils in magnetically opposed relation, one of said coils being controlled by said mechanism, in combination with a remote control box having manually adjustable means for controlling the other coil of said device, a pair of normally open switch members in said box, each switch member being connected in the circuit of one of said coils, a finger piece on said box for closing both of said switch members, means whereby said finger piece when released automatically opens said switch members, and electrical connections whereby said mechanism is

operative as long as either coil predominates in said electromagnetic device, said mechanism stopping when the electromagnetic effects of said coils are substantially balanced.

12. Electric driving mechanism which includes 5 as electromagnetic controlling device comprising a pair of coils in magnetically opposed relation, a rheostat operated by said mechanism for controlling one of said coils, in combination with a remote control box having a normally open 10 switch in the circuit of each coil, a manually adjustable rheostat for selectively controlling the other coil, and a single finger piece for operating said rheostat and both of said switches, said mechanism being operative when either coil predominates and stopping when said coils are substantially balanced in their electromagnetic effects. 15

ADOLPH A. THOMAS.
